UNITED STATES PATENT OFFICE

2,141,131

GUIDE DEVICE

Stevenson Findlater, McKeesport, Pa., assignor to
 National Tube Company, a corporation of New
 Jersey

Application March 26, 1938, Serial No. 198,307

4 Claims. (Cl. 80—13)

This invention relates to apparatus for making metallic tubular work-pieces, and more particularly to guide devices therefor.

In my copending applications, Serial No. 5 100,535, filed September 12, 1936, and entitled "Apparatus for making tubular work-pieces" and Serial No. 112,588, filed November 24, 1936, and entitled "Guide device", there are disclosed sectional guide devices for tube rolling mills. The 10 device of the present application is generally similar thereto but is designed to more readily permit changing the guide device to accommodate work-pieces of various sizes.

It is among the objects of the present invention 15 to effectively sectionalize seamless tube rolling mill guide devices and provide for their efficient support as a unitary structure; the guiding sections or elements being relatively small to eliminate large discards of unworn parts.

20 It is a further object of the present invention to provide a sectionalized seamless tube mill guide device in which the worn sections are readily replaced and which is capable of being quickly and readily changed to provide different sized guide 25 passes.

The foregoing and further objects will be apparent after referring to the drawing in which:

The sole figure is a sectional elevation of the 30 device of the invention as applied to a conventional type of seamless tube mill.

Referring more particularly to the drawing, the numerals 1 and 2 respectively designate upper and lower chairs for the guide devices of the present invention, which are disposed above and 35 below the pass-line of the mill and intermediate the metal-working rolls.

According to the teachings of the invention, the upper chair 1 carries a horizontally extending pin 3 disposed adjacent the inlet end of the mill.

40 This pin 3 carries a movable bell-crank lever 5, one end of which extends rearwardly and generally horizontally as shown at 6. One end of a vertically extending shaft 7 is pivotally connected, as at 8, to the end 6 of the bell-crank lever 5.

45 The other end of the shaft 7 is shown as extended through an ear 9 which may be integrally formed on the upper chair 1. This end of the shaft 7 is screw-threaded to carry an adjusting nut 10 in contact with the ear 9, whereby the bell-crank lever 5 may be partially rotated on the pin 3.

50 The other end of the bell-crank lever 5 extends downwardly as shown at 12, and carries a rearwardly extending lug 13 whose rearward face 14 is inclined downwardly and rearwardly.

55 The rearward part of the upper chair 1 has a

downwardly and forwardly projecting lug 16 having a downwardly and forwardly inclined face 17 which, together with the supporting surface 18 of the chair 1, defines a reentrant angle 19.

Adapted to be disposed on the chair 1 and held 5 in place between the surface 14 of the bell-crank lever 5 and in the reentrant angle 19 is a guide-element holder 21 which can vary in depth to accommodate the guide to a large range of pipe sizes. Guide-element holder 21 has a pair of forwardly and rearwardly extending lugs 22 and 23. Forward lug 22 has a forwardly and upwardly inclined surface 24 which is complementary to the surface 14 on the bell-crank 5 while the rearward lug 23 which is adapted to be disposed in the reentrant angle 19 has a rearwardly and upwardly extending surface 25 which is complementary to the inclined surface 17.

The rearward and lower part of the guide-element holder 21 has a downwardly and forwardly projecting portion 36 having an upwardly and rearwardly inclined surface 37 projected below the guide-element supporting surface 38 which, together with the inclined surface 37, forms a reentrant angle 39.

This guide-element holder 21 carries a horizontally extending pin 4 on which is pivotally mounted a bell-crank lever 26, one end of which extends rearwardly through the guide-element holder 21, as shown at 27. One end of a vertically 30 extending shaft 28 is pivotally connected, as at 29, to the end 30 of the bell-crank lever 26. The other end of the vertical shaft 28 is extended through an ear 31 which may be integrally formed on the upper chair 1. This end of the shaft 28

35 is screw-threaded to carry an adjusting nut 32 in contact with the ear 31 whereby the bell-crank lever 26 may be partially rotated on the pin 4. The other end of the bell-crank lever 26 extends downwardly, as shown at 34. This end of the bell-crank lever 26 forms an arm 34 which has a suitably contoured guiding surface 35 and forms part of the sectionalized guide device of my invention.

The rearward end of the lower end of the arm 34 of the bell-crank lever 26 has a forwardly and 40 upwardly inclined surface 35a.

A guide-element 40 is adapted to be disposed on the supporting surface 38 and is of a generally trapezoidal shape in longitudinal cross-section having opposed front and rear inclined surfaces 50 41 and 42 which are complementary to the inclined surfaces 35a and 37 on the bell-crank lever 26 and the guide-element holder 21, respectively. It is therefore seen that the guide-element 38 can be rigidly clamped on the guide-

element holder 21 by adjusting the bell-crank lever 26. The suitably contoured face 35 of the bell-crank lever 26 and the guide-element 38 together form the upper guiding surface of the 5 sectionalized guide device.

The guide device can be readily changed to accommodate a wide variety of sizes with a relatively small stock of parts. Thus a few sizes of the guide-element holder 21 and bell-crank lever 10 26 can be used to vary the size of the guide over a wide range, and smaller adjustments can be made by having guide-elements 40 of suitable thickness and contour for the various sizes of pipe rolled in the mill.

15 The lower chair 2 of the sectionalized guide device of my invention is suitably recessed at the mid-portion thereof as shown at 50 and carries two horizontally extending pins 51 and 52. Pin 51 carries a vertically extending lever 54 which 20 has a rearwardly extending lug 55 provided with an upwardly and rearwardly extending face 56.

Seated within the recess 50 is a guide-element holder 65 which may be of different depths to accommodate the guide device to a wide range 25 of tubular work-pieces. At the forward end of the guide-element holder 65 is an upwardly extending lug 66 which is provided with forward and rearward upwardly-and-rearwardly inclined faces 67 and 68 respectively. Forward face 67 30 is inclined at an angle which is complementary to the face 56 of the lever 54. Rearward face 68, together with the upper surface 69 of the guide-element holder 65, defines a reentrant angle 70. The rearward end of the guide-element holder 35 65 carries a horizontally extending pin 53 on which is pivotally mounted a vertically extending lever 57 which engages the chair 2, as at 58, and has a forwardly extending lug 59 provided with an upwardly and forwardly extending face 40 60.

Disposed on the guide-element holder 65 is a guide-element and holder 71 which has, adjacent its forward end, an upwardly and rearwardly inclined surface 72 complementary to the rearward 45 face 68 of the holder 65 and adapted to fit in the reentrant angle 70. The guide-element and holder 71 has a forward upwardly projecting lug 73 of considerable length which is suitably profiled and has a guiding surface 74 similar to the 50 surface 35 of the bell-crank lever 26 on the upper chair 1. The rearward part of the upwardly projecting lug 73 is mitered to provide a rearwardly and upwardly inclined surface 75 which, together with the horizontally extending supporting surface 55 76 of the holder portion of the guide-element and holder 71, forms a reentrant angle 77.

A guide-element 80, which is similar to and preferably interchangeable with the upper guide-element 40, is adapted to be disposed on the supporting surface 76 of the holder portion of the 60 guide-element and holder 71, and is of a generally trapezoidal shape in longitudinal cross-section having opposed front and rear inclined surfaces 81 and 82 which are complementary to the inclined surfaces 75 and 60 on the guide-element and holder 71 and lever 57, respectively. It is 65 therefore seen that the guide-element and holder 71 and the guide-element 80 can be rigidly clamped in position by adjusting the lever 54. The inner faces of the guide-element and holder 71 and the guide-element 80 thus form the lower 70 guiding surface of the sectionalized guide device.

As in the case of the upper part of the guide device the lower part can be readily changed to 75 accommodate a wide variety of sizes very easily

with a relatively small stock of parts. Thus a few sizes of the guide-element holder 65 can be used to vary the size of the guide-pass over a wide range, and small adjustments can be made by having guide-element and holders 71 and 5 guide-elements 80 of suitable thickness and contour for the various sizes of pipe rolled in the mill.

A cannon or circular inlet guide 90 may be suitably disposed on the forward end of the lower 10 chair 2 and on outlet guide trough 91 on the rearward end. The outlet guide trough 91 is held in position by a clamp 92 which is adjusted by a nut 93 on the rearward end of a rod 94 which is pivotally connected at its forward end, as at 15 95, to the lever 54 and extends rearwardly through the clamp 92. Thus it is seen that adjustment of the nut 93 not only secures the trough 91 in position but also rigidly secures guide-elements 71 and 80 on the guide-element holder 65 by 20 clamping the assembly between the lever 54 and lever 57 which is forced into engagement with the lower chair 2 at 58.

While I have shown and described a specific embodiment of my invention, it will be understood that I do not wish to be limited exactly thereto as various modifications may be made within the scope of the following claims.

I claim:

1. In an apparatus for making metallic tubular work-pieces, said apparatus including a plurality of power-actuated metal-working rolls constructed and arranged to advance the work-piece helically, guide supports disposed immediately above and below the pass formed by said rolls, and guide devices carried by said guide supports, one of said guide devices comprising a lever pivoted intermediate its ends and provided with a portion adapted to contact the work-piece, a guide-element clamped in position by said lever, a spacer for positioning said guide-element with respect to the adjacent guide support, the other of said guide devices comprising a pair of sectionalized elements, a spacer for positioning said sectionalized elements with respect to the guide support, and means for clamping said sectionalized elements and said spacer to the adjacent guide support, one of said sectionalized elements having a portion extending between the other sectionalized element and said spacer to thereby provide rigidity. 40

2. In an apparatus for making metallic tubular work-pieces, said apparatus including a plurality of power-actuated metal-working rolls constructed and arranged to advance the work-piece helically, a guide support disposed intermediate said metal-working rolls, a totally stationary guide device carried by said guide support, said guide device comprising a pair of sectionalized elements, each of said elements being 45 adapted for substantially continuous contact with that portion of the work-piece which is in the working zone of said metal-working rolls, and means for clamping said sectionalized elements to the adjacent guide support, one of said sectionalized elements having a portion extending between the other sectionalized element and said support to thereby provide rigidity. 55

3. In an apparatus for making metallic tubular work-pieces, said apparatus including a plurality of power-actuated metal-working rolls constructed and arranged to advance the work-piece helically, a guide support disposed intermediate said metal-working rolls, a totally stationary guide device carried by said guide 70 support, said guide device comprising a pair of sectionalized elements, each of said elements being 75 adapted for substantially continuous contact with that portion of the work-piece which is in the working zone of said metal-working rolls, and means for clamping said sectionalized elements to the adjacent guide support, one of said sectionalized elements having a portion extending between the other sectionalized element and said support to thereby provide rigidity. 75

support, said guide device comprising a pair of sectionalized elements, each of said elements being adapted for substantially continuous contact with that portion of the work-piece which is in the working zone of said metal-working rolls, a spacer for positioning said sectionalized elements with respect to the guide support, and means for clamping said sectionalized elements and said spacer to the adjacent guide support, 5 one of said sectionalized elements having a portion extending between the other sectionalized element and said spacer to thereby provide rigidity.

4. In an apparatus for making metallic tubular work-pieces, said apparatus including a plurality of power-actuated metal-working rolls constructed and arranged to advance the work- 10

piece helically, a guide support disposed intermediate said metal-working rolls, a totally stationary guide device carried by said guide support, said guide device comprising a pair of sectionalized elements, each of said elements being adapted for substantially continuous contact with that portion of the work-piece which is in the working zone of said metal-working rolls, a spacer for positioning said sectionalized elements with respect to the guide support, and 15 opposed clamping means for rigidly securing said sectionalized elements to said spacer and said spacer to the adjacent guide support, one of said sectionalized elements having a portion extending between the other sectionalized element and 15 said spacer to thereby provide rigidity.

STEVENSON FINDLATER.
